SUCTION CLOTHESBRUSH

Agnes Lenz Schmidt, Beverly Hills, Calif.

Application September 13, 1943, Serial No. 502,205

1 Claim. (Cl. 15—7)

My invention relates to clothes brushes, and has among its objects and advantages the provision of an improved brush of the suction cleaning type.

In the accompanying drawing:

Figure 1 is a side elevational view of a brush; Figure 2 is a bottom plan view; and Figure 3 is a sectional view along the line 3—3 of Figure 2.

In the embodiment selected for illustration, the brush 10 comprises a body 12 to which is secured a brush unit 14, the latter comprising bristles 16 anchored in a ring 18 secured to the body 12, as by screws 20. Body 12 is oval-shaped when viewed according to Figure 2 so as to provide a brush shaped to be conveniently grasped in the hand. Brush unit 14 is similarly contoured, with the bristles 16 arranged in an oval-shaped row extending about the perimeter of the body 12.

Body 12 is recessed at 22 for the reception of a bag 24 such as is employed in conventional vacuum cleaners, with the exception of its size. Bag 24 as well as an electric motor 26 is enclosed by a cover 28 hingedly connected with the body 12 by hinges 30. A latch 32 secures the cover 28 to the body 12 in the closed position of the cover.

Centrally of the body 12 is provided a chamber 34 within which is located a fan 36 attached to the motor shaft 38. Chamber 34 has communication with the bag 24. One end of the body 12 is provided with an insulative sleeve 40 for the accommodation of the circuit wires 42, the body being grooved at 44 to accommodate passage of the wires to the motor.

In addition to performing the functions of an ordinary clothes brush, the brush in the instant case embodies a suction action which collects the dust, lint and the like for delivery to the bag 24. Because of the oval-shaped contour of the brush structure, the brush is narrow

in width but has considerable length so as to cover a relatively wide area. The bristle unit 16 is in the nature of an oval-shaped ring so as to provide a cavity having communication with the chamber 34. The length of the bristles and the ring 18 space the body 12 sufficiently far from the surface being brushed to maintain communication between the entire cavity defined by the bristle unit 16 and the chamber 34.

A closure plate 46 extends across the upper end of the recess 34. Air outlet openings 48 are provided in the cover 28 so as to relieve back pressure from the bag 24.

Without further elaboration, the foregoing will so fully illustrate my invention, that others may, by applying current knowledge, readily adapt the same for use under various conditions of service.

20 I claim:

A suction clothes brush, comprising a substantially oval-shaped body having its lowermost side provided with a concaved center portion formed with an inlet port and a broad flat face rim area about the same, a hand-palm fitting upwardly arched outer smooth faced cover crowning the uppermost side of the body for access to its interior and marginally flush therewith, a motor driven suction fan removably counter-seated in the body and wholly concealed by the cover, and having a bladed fan wheel next to the said port, a dust collector bag removably secured to the fan and detachably confined in the body by said cover, and a flat faced ring-like bristle unit marginally free and completely overlying the rim area throughout its broad face and wholly outside of the concaved center portion, and fasteners securing the rim area and unit together at points innermost to the lay of the bristles of the latter.

AGNES LENZ SCHMIDT.
